DESIGN FOR A COMBINED LAMP AND ATTACHING CLIP

Raymond Zurawin, New York, N. Y.

Application May 6, 1940, Serial No. 92,179

Term of patent 7 years

To all whom it may concern:

Be it known that I, Raymond Zurawin, a citizen of the Polish Republic, who have filed my intention of becoming a citizen of the United States, residing in New York, in the county of New York and State of New York, have invented a new, original, and ornamental Design for a Combined Lamp and Attaching Clip, of which the following is a specification, reference being had to the accompanying drawing, forming part hereof.

Fig. 1 is a front elevational view, in perspective, of a combined lamp and attaching clip, showing my new design; and

Fig. 2 is a side elevational view thereof.

The dominant features of my design reside in the portions shown in full lines.

I claim:

The ornamental design for a combined lamp and attaching clip, as shown and described.

RAYMOND ZURAWIN.
